UNITED STATES PATENT OFFICE.

WILHELM ENGEL, OF NIED, NEAR FRANKFORT-ON-THE-MAIN, GERMANY.

SEAL LOCK.

Application filed May 22, 1922. Serial No. 562,833.

To all whom it may concern:

Be it known that I, WILHELM ENGEL, a citizen of the German Republic, and a resident of Nied, near Frankfort-on-the-Main, 5 Germany, have invented a new and useful Improved Seal Lock, of which the following is a specification.

This invention relates to a seal lock for cars, storage rooms and the like. The lock 10 constructed according to this invention, consists of a hollow, cylindrical bolt which is adapted to be inserted into casing, and the upper portion of which projects beyond the casing and retains a locking ring; where- 15 as the body of the bolt, which lies within the casing, is coupled with the latter by locking means that lock it automatically when it is put in place, but require the application of a special key to release the bolt and enable 20 the lock to be opened. An essential feature of my invention resides in the cooperation of the bolt with a locking ring for effecting the locking action proper and furthermore in its adaptation for the reception of a seal or 25 what may be termed a "lead" for sealing purposes, as will be more fully described hereinafter.

To this end, I refer to the accompanying drawing, in which similar letters of reference denote similar parts throughout the 30 several views, and in which Figure 1 is a vertical section of the lock; Fig. 2 is a horizontal section on the line 2-2 of Fig. 1; Fig. 3 is a side view of the bolt; Figs. 4 and 5 are side views of the key, at right 35 angles to each other; Fig. 6 is a transverse section of the key on the line 6-6 of Fig. 5; Fig. 7 is a composite view showing two seals or "leads," the left-hand seal being in normal condition, the right-hand seal being 40 punched; and Fig. 8 is also a composite view showing the lead container or case in plan and in side elevation.

The lock consists chiefly of two parts, viz., 45 the casing *a* and the bolt *b*. The casing is affixed to the wall of the car, or to the frame of the door, to be locked, by means of bolts, for which a hole or holes *i* in a lug *h*, is provided. The lock casing is made of iron or 50 steel and has one or more inner annular flanges or projections *k*, each preferably formed with an inwardly inclined top surface. The upper end of the casing is contracted so as to form a neck *m* provided with 55 an inwardly projecting shoulder *k'* similar to the flange *k*. Through the bottom of the

casing extends inwards and upwards a tube *d* which serves as a guide for the key.

The bolt *b* is a hollow cylindrical body which has vertical slots *b'* in its wall. At 60 the two sides of each slot, eyes *e* are provided, having pins *o* carrying pawls *n*. The normal position of these pawls is that shown in Fig. 1, for they are held in this position with their lower ends *n'* abutting against the 65 wall of the bolt *b* by the weight and overhang of their upper portions; but if desired, springs may be provided to assist in holding them in that position. In this position, the upper ends of the pawls lie below the projections *k* and *k'*. They move radially in- 70 ward when the bolt is introduced into the casing.

The bolt *b* has below its head a transverse recess *g* for the reception of a case *r* containing the seal or lead and comprising two parts which are connected by a hinge *r'* and each of which has a central hole, preferably of a special shape as shown at *r''* in Fig. 8. The hole is closed by a piece *p* of paper, 80 paste-board, lead or the like constituting the seal, which is placed between the two members forming the case or frame *r* and which serves to receive suitable inscriptions or the like. The head of the bolt has lateral recesses *s* and a peripheral flange *t*, the diameter of which latter corresponds approximately to that of the casing *a*. Hinged to the head or flange at *t'* is a cover *z* which 85 closes the central aperture *t* provided over 90 the recess *g*.

The lock ring *f* which is to be coupled with the neck of the lock casing *a* is adapted to be turned, as well as displaced axially, upon a bolt *y* affixed to the door to be locked. 95 In its locking position, the ring takes over the neck *m* of the casing, as shown in Fig. 1. The bolt *b* is inserted after the ring *f* has been placed upon the casing; but prior to doing this, the seal *p* is inserted in the case *r*, 100 and this latter is then placed in the recess *g* of the bolt. This having been done, the bolt *b*, which has an aperture *b''* in its bottom, is inserted into the casing with its ap- 105 pertured bottom riding down on the guide tube *d*. When the bolt reaches its lowermost position, the pawls *n* fall back below the pro- 110 jections *k* and *k'*, respectively, with their noses *q* engaging in the slots *b'*, whereby the bolt is locked, as is, consequently, also the ring *f*.

Opening of the lock can be effected only

with the aid of the key shown in Figs. 4 and 5. This key consists of a hollow body *c* having a rib or feather *u* adapted to engage in a groove *u'* in the bolt *b*, and having, 5 furthermore, an internal pin *c'* to engage in the tube *d*. These members *u* and *c'* serve for guiding the key while it is being put in place. There are also outer lugs *v* distributed over the circumference and the 10 length of the key body *c*. The number and position of these lugs *v* correspond to the number and position of the pawls *n*, the nose or projection *q* on each pawl being adapted to co-operate with one of the lugs *v*. 15 As the latter engage with the noses *q*, the pawls *n* are turned upon their supporting pins *o* and caused to disengage the projections *k* and *k'*, respectively, so that the bolt *b* is then no longer locked, but ready to be 20 withdrawn. To facilitate withdrawal of the bolt the key is provided with two pawl-like levers *w* hinged at *x* to the key and having broadened portions or plates *l* constituting finger-pieces. Preferably springs 25 may be provided, which tend to spread the levers or arms *w* away from the key-body *c*, and which are compressed when the arms *w* are moved into the position shown in Figs. 4 and 5. The gripping ends of the 30 members *w* are intended to engage in the recesses *s*, or in an inner circumferential groove, provided at the top of the bolt *b*, so that the latter can be withdrawn by means of the key, i. e., with the aid of the pawls 35 *w* engaging in the recesses *s*.

It is obvious that the key can be inserted only by destroying the seal *p*. In being forced down into the tube *d* of the bolt *b*, the key will punch the seal *p* in the manner 40 shown in the right-hand half of Fig. 7.

If springs are provided in connection with the arms *w*, the latter will be adapted to engage automatically in the recesses *s*. To separate the key from the bolt, the pawls 45 *w* are moved inward so that their gripping ends may be disengaged from said recesses.

The key is required only for opening the lock, while the closing thereof is effected by the bolt *b*.

50 While I have shown specific structural details, I desire it to be understood that my invention is not restricted thereto, but that any equivalent means accomplishing substantially the same results may be used 55 without departing from the spirit and scope of my invention.

I claim as my invention:

1. In a seal lock, the combination of a case; a locking ring engageable with the 60 case; a bolt insertable through said ring into the interior of the case to hold the two in locked relation, said bolt having a seal-receiving space therein; cooperating locking devices within said case provided on the 65 latter and on the bolt to prevent withdrawal

of said bolt; and a key for releasing said locking devices adapted to break a seal in said space incidental to its operation.

2. In a seal lock, the combination of a case; a locking ring engageable with the 70 case; a bolt insertable through said ring into the interior of the case to hold the two in locked relation, said bolt having a seal-receiving space therein; locking members movably mounted on said bolt; cooperating 75 parts on the interior of said case automatically engaged by said locking members when said bolt is inserted into the case to prevent its withdrawal therefrom; and a key engageable with said bolt to release said 80 locking members and incidentally break a seal in said space.

3. In a seal lock, the combination of a case; a locking ring engageable with the 85 case; a tubular bolt insertable through said ring into the interior of the case to hold the two in locked relation, said bolt having a seal-receiving space therein; locking members movably mounted on said bolt; cooperating parts on the interior of said case automatically engaged by said locking members when said bolt is inserted into the case 90 to prevent its withdrawal therefrom; and a key insertable through a seal in said space and into said bolt to release said locking 95 members.

4. In a seal lock, the combination of a case; a locking ring engageable therewith; a tubular bolt insertable through said ring into the interior of the case to hold the two 100 in locked relation, said bolt having a seal-receiving space therein and also having a plurality of longitudinal slots; a locking pawl pivotally mounted directly opposite each slot and extending inwardly through 105 the same at one end; a plurality of cooperating projections on the interior of the case automatically engaged by the outer ends of the pawls when said bolt is inserted into said case to prevent its withdrawal 110 therefrom; and a key insertable through a seal in said space into said bolt to engage the inner ends of the pawls and release them from said projections.

5. A seal lock, according to claim 4, in 115 which the surface of the key is provided with releasing lugs corresponding in number and position to the locking pawls and adapted to engage the inner ends of the pawls.

6. In a seal lock, the combination of a case; a locking ring engageable with the 120 case; a tubular bolt insertable through said ring into the interior of the case to hold the two in locked relation, said bolt having a 125 seal-receiving space therein; locking members movably mounted on said bolt; cooperating parts on the interior of said case automatically engaged by said locking members when said bolt is inserted into the case 130

to prevent its withdrawal therefrom; and a key insertable into said bolt to release said locking members and incidentally break a seal in said space, said key and bolt constituting companion parts, one of which is formed with a longitudinal guide groove and the other with a rib slidable therein.

7. In a seal lock, the combination of a case; a locking ring engageable therewith; a tubular bolt insertable through said ring into the interior of the case to hold the two in locked relation, said bolt having a seal-receiving space therein and also having a plurality of longitudinal slots; a locking pawl pivotally mounted directly opposite each slot and extending inwardly through the same at one end; a plurality of cooperating projections on the interior of the case automatically engaged by the outer ends of the pawls when said bolt is inserted into said case to prevent its withdrawal therefrom; and a key insertable through a seal in said space into the said bolt to engage the inner ends of the pawls and release them from said projections, said key and bolt constituting companion parts, one of which is formed with a longitudinal guide groove and the other with a rib slidable therein.

30 8. In a seal lock, the combination of a case; a locking ring engageable with the case; a tubular bolt insertable through said ring into the interior of the case to hold the two in locked relation, said bolt having a seal-receiving space therein; locking members movably mounted on said bolt; cooperating parts on the interior of said case automatically engaged by said locking members when said bolt is inserted into the case to prevent its withdrawal therefrom; and a key insertable into said bolt to release said locking members and incidentally break a seal in said space, said key and bolt having interfitting guiding members.

45 9. In a seal lock, the combination of a case; a locking ring engageable with the case; a tubular bolt insertable through said ring into the interior of the case to hold the two in locked relation, said bolt having a

seal-receiving space therein; locking members movably mounted on said bolt; cooperating parts on the interior of said case automatically engaged by said locking members when said bolt is inserted into the case to prevent its withdrawal therefrom; a key insertable into said bolt to release said locking members and incidentally break a seal in said space, said key embodying a tubular body and a central guide pin which is spaced from the wall of said body; and a fixed tubular member disposed centrally within said bolt to receive the guide pin of the key when the latter is inserted into the bolt.

10. In a seal lock, the combination of a case; a locking ring engageable therewith; a tubular bolt insertable through said ring into the interior of the case to hold the two in locked relation, said bolt having a seal-receiving space therein; cooperating locking devices within the case provided on the latter and on the bolt to prevent withdrawal of said bolt; a key insertable into the bolt to release said locking devices and incidentally break a seal in said space; and means on said key engageable with said bolt to withdraw the same when the key is withdrawn.

11. In a seal lock, the combination of a case; a locking ring engageable therewith; a tubular bolt insertable through said ring into the interior of the case to hold the two in locked relation, said bolt having a seal-receiving space therein; cooperating locking devices within the case provided on the latter and on the bolt to prevent withdrawal of said bolt; a key insertable into the bolt to release said locking devices and incidentally break a seal in said space; and gripping pawls on said key engageable with the bolt when the key is inserted thereinto, and adapted to withdraw said bolt when the key is withdrawn.

In testimony whereof I affix my signature in presence of a witness.

WILHELM ENGEL
